UNITED STATES PATENT OFFICE.

EDMUND LYON, OF ROCHESTER, NEW YORK.

LOCOMOTIVE TURN-TABLE.

SPECIFICATION forming part of Letters Patent No. 359,220, dated March 8, 1887.

Application filed March 22, 1886. Serial No. 196,183. (No model.)

To all whom it may concern:

Be it known that I, EDMUND LYON, a citizen of the United States, residing at Rochester, Monroe county, and State of New York, have 5 invented certain new and useful Improvements in Locomotive Turn-Tables, of which the following is a specification.

My invention relates to the construction of locomotive turn-tables, and the object is to 10 afford a feasible way of operating or rotating a turn-table by means of the locomotive run thereon. I attain this object by employing friction-wheels which are adapted to receive motion from the drive-wheels of the locomotive, gearing to utilize this motion for the 15 purpose of rotating the turn-table, and also locking and blocking devices. All of this mechanism is illustrated in the accompanying drawings, in which—

20 Figure 1 is a vertical section of the pit and a vertical central longitudinal section of the turn-table. Figs. 2 and 3 are plan views. Fig. 4 is a cross-section in line 1 1 of Fig. 1. Fig. 5 is a vertical section in line 2 2 of Fig. 2. Fig. 25 6 is a vertical section of the shaft S in line 3 3 of Fig. 3.

Similar letters refer to similar parts throughout the several views.

A represents the frame, and B the central 30 step or bearing, of a locomotive turn-table. At or about the places occupied by the drive-wheels of a locomotive when the latter is run on the turn-table the rails are removed, and in lieu thereof are employed sets of friction-wheels D E, whose upper edges are in line 35 with the lap of the rail and whose axles d e rest horizontally in suitable bearings in the frame A. These friction-wheels are adjusted so that they overlap each other, and thereby 40 for some distance form a very perfect substitute for the portion of rail which is displaced. This adjustment affords great facility in bringing the drive-wheels into position, and, by reason of such stable and ample support, makes 45 it a comparatively easy matter to retain them in that position while the table is being rotated. Should it be thought desirable to utilize all the force imparted to these friction-wheels their axles d e may be geared together 50 by means of cog-wheels C D' E'. This, how-

ever, is not essential to the operation of the motive mechanism.

One end of the shaft G is geared to the axle d by the cog-wheels d' g'. A duplicate of this shaft, with its gearings, may be employed in 55 the other half of the turn-table, as indicated; but such duplication is not a matter of necessity. The lower end of the shaft G is provided with the cog-wheel g, which meshes with the stationary circular rack H under the table. 60 This rack is protected from slush, ashes, &c., by being inverted and having the covering-flange h.

The lower portion of the shaft G is supported by the bearing J, which is held laterally in position by the brace I, but is otherwise controlled by the connecting-rods K K' and lever L. By this lever the bearing J may be lowered and the cog-wheel g thrown out of gear with the rack H when the turn-table is 70 to be rotated by other means than the motive mechanism.

To prevent the ungearing of the cog-wheel g by the rocking of the frame A, the spiral spring k is employed on the upper end of the 75 rod K, which keeps it constantly in contact with the rack. Concerning the arrangement of this spring more will presently be said.

Both the locking and the blocking devices are operated from the locomotive by means of 80 the inclined lever M, which is a part of a system of levers and connecting-rods so arranged that the act of unlocking the turn-table blocks the drive-wheels of the locomotive, and vice versa.

At its lower end the lever M is fulcrumed to the frame A, and a little higher up passes through an elliptical opening in the connecting-rod N, which is journaled to the connecting-rod O.

The connecting-rods P and O are journaled at one end to the end of the rocking lever Q, which is fulcrumed at its center to the frame A and at the other end, respectively, to the block T and the lock-shaft S. With the latter is employed the spiral spring s', which is supported and confined by mutilated disks placed in either end of the slot of the lock-shaft S, as indicated in Fig. 6. If thought best, the disk x may be discarded, in which 90 95 100

event one end of the spring s' will rest against the connecting-rod O . A similar arrangement holds the spiral spring k in place. To the outer end of the lock-shaft S is journaled the 5 horizontal wheel s .

The block T is substantially **U**-shaped in cross-section. Its lower limb rests on the frame A between the guides $a a$, which hold it laterally in position. Its upper limb is furnished with the horizontal rollers $t t$, which lie at right angles to the track. The under surface of the upper limb is on a level with the top of the track, so that when the block is drawn toward it the rail is embraced by the two limbs 15 of the block.

When a locomotive is to be turned, the locking and the blocking devices are arranged as shown in Figs. 1 and 2, which is the position for receiving or discharging a locomotive.

20 After the locomotive has been run on the turn-table and its drive-wheels rest upon the friction-wheels, the upper end of the lever M is drawn toward it, causing the locking and the blocking devices to assume the position 25 indicated in Fig. 3. The drive-wheels are then allowed to revolve slowly, which, being prevented from advancing by coming in contact with one of the rollers of the block T , set the friction-wheels in motion, the shaft G revolves, the cog-wheel g travels along the rack H , and the turn-table begins to rotate. On 30 nearing the desired place for discharging the locomotive the steam is shut off and the upper end of the lever M pressed steadily outward. 35 This forces the wheel s against the inside of the pit around which it travels, readily passing all irregularities until it reaches and enters the **V**-shaped socket V . As the inertia of the turn-table urges it up the opposite incline of the socket the spiral spring s' is compressed and the table brought gradually to a standstill without experiencing any shock. With the expansion of the spiral spring s' the 40 wheel s is compelled to retreat into the angle 45 of the socket, and the turn-table is permitted to assume a proper position for discharging the locomotive.

Having described my invention, what I desire to claim, and secure by Letters Patent, is—

50 1. The combination, with a turn-table, of friction-wheels having horizontal axes and be-

ing adapted to receive motion from a locomotive-engine on said table, said friction-wheels being so adjusted that two of them at a time may be in contact with the same drive-wheel, 55 and suitable gearing connected with the turn-table, whereby the table may be turned by said engine, substantially as shown and described.

2. The combination, with a turn-table, of friction-wheels having horizontal axes and being adapted to receive motion from a locomotive-engine on said table, said friction-wheels being so adjusted that those adjacent overlap each other, and suitable gearing connected with the turn-table, whereby the table may be 60 turned by said engine, substantially as shown and described.

3. A turn-table having friction-wheels whose axes are horizontal, in combination with gearing and a stationary circular rack, said friction-wheels being operated by the drive-wheels of the locomotive-engine on the table, and the gearing connecting with the rack, whereby the 70 table is turned, substantially as shown and described.

4. The combination, with a turn-table adapted to be turned by a locomotive-engine resting thereon, of a stationary inverted rack, and gearing of the turn-table, constructed substantially as described, engaging with the rack, 75 substantially as and for the purpose specified.

5. The combination, with a railroad-track, of a blocking device consisting of a block substantially **U**-shaped in cross-section, one of whose arms is furnished with one or more rollers, said blocking device being movable out and in, substantially as shown and described. 85

6. In a turn-table, the combination, with the lock-shaft, of a wheel or roller journaled thereto, substantially as and for the purpose specified.

7. The combination, with a slotted shaft, of a spiral spring one end of which is supported by a mutilated disk placed in the slot, and means whereby the other end of said spring 95 may be supported, substantially as shown and described.

EDMUND LYON.
